UNITED STATES PATENT OFFICE.

CHARLES H. McDONALD, OF SPRINGFIELD, OHIO.

PICKET ALARM.

Application filed October 25, 1918. Serial No. 259,671.

To all whom it may concern:

Be it known that I, CHARLES H. McDONALD, a citizen of the United States, residing at Springfield, in the county of Clark and State of Ohio, have invented new and useful Improvements in Picket Alarms, of which the following is a specification.

This invention comprehends generally improvements in picketing alarms and more particularly relates to an alarm attachment for bayonets.

It is the principal aim and object of the present invention to provide a device of the above mentioned character designed to be attached to a bayonet, two of the devices being preferably employed, while the supporting bayonets are anchored in an upright position in the ground and between the device or attachment proper is arranged a string, which, when engaged by one of the enemy when out on an investigating trip, will release the attachment so as to sound an alarm and thereby indicate to the pickets the presence of one or more of the enemy in the immediate vicinity.

More particularly this invention contemplates the provision of a device of the above mentioned character designed to be connected to the handle of a bayonet and embodying a casing in which is detachably connected a barrel while positioned in the casing and acting in conjunction with the cartridge in the barrel is improved firing means releasable at a certain time for firing the cartridge and consequently sounding an alarm.

It is a more specific object of this invention to provide improved means for releasably retaining the firing means in inoperative position.

Among the other aims and objects of this invention may be recited the provision of a device of the character described with a view to compactness, and in which the number of parts are few, the construction simple and the cost of production low and the efficiency high.

Other improvements and novel details in the construction and arrangement of the various parts of the apparatus will be brought out more in detail in the description to follow, which for a clear understanding of the invention should be considered in connection with the accompanying drawings forming a part hereof, and wherein is disclosed for the purpose of illustration a convenient and

satisfactory embodiment of the invention. It is to be noted in this connection that minor changes in the construction and arrangement of parts may be made without departing from the principle of operation of the various parts.

The invention is clearly illustrated in the accompanying drawings, in which—

Figure 1 is a side elevation showing two of the devices operatively connected to each other.

Figure 2 is a vertical sectional detail of one of the attachments, and

Figure 3 is a vertical sectional view taken on line 3—3 of Figure 2.

Similar characters of reference are employed in all of the above described views, to indicate the corresponding parts.

Referring now, more particularly, to the accompanying drawings, there is illustrated a pair of bayonets generally designated by the numeral 1 of a conventional construction and these bayonets are adapted to be anchored perpendicularly to the ground, while detachably connected to the handle portions of each of these bayonets is one of the improved signal alarms indicated in its entirety by the numeral 2, being operably connected to each other through the instrumentality of cord or cable 3 in a manner hereinafter to become apparent.

In the present instance, each signal alarm consists of a cylindrical casing 4 formed with an attaching plate 5 having openings 6 therein through which pass suitable fasteners 7 for the removable connecting of the devices to the handle of one of the bayonets. The upper end of each casing 4 is threaded exteriorly as at 8. A barrel 9 of the tubular configuration is now employed and is reduced and threaded interiorly as at 10 leaving an annular shoulder 11 against which is arranged the flanged cap 12 of the cartridge 13 when the latter is positioned in the barrel. Subsequent to the engagement of the cartridge the barrel is engaged through the instrumentality of the threads 10 on the threaded portion 8 of the casing as indicated in the drawings.

In order to fire the cartridge a plunger pin or rod 14 is disposed in the casing and is formed near its inner end with a plunger or disc head 15 while also disposed in the casing about the rod is a coiled expansion spring 16 the respective ends of which bear against the head 15 and the lower closed end

of the casing 4 so as to normally exert a pressure on the head. Another head on knob 17 is connected to the outer projecting end of the rod and facilitates the retracting of 5 the head or plunger 15 against the pressure of the spring 16.

With a view towards providing the improved means for normally holding the firing pin in a retracted position, an ear 18 10 projects from the plate 5 while pivotally connected at its inner end to this ear by means of the pintle 19 is a trip arm 20 designed to operate in the horizontal or transverse slot 21 in the casing so as to be disposed in front of the head 15 subsequent to the retracting thereof. The outer end of the arm is formed with an eye 22 in which is engaged one end of the cable 3 and this cable which is engaged at its respective ends 20 and the outer ends of the arms 20 to the device is also adapted to be disposed about a foot or so above the ground so that when one of a party of the enemy when out on a scouting trip engages the same the arms 20 25 will swing horizontally and release the head which is shot forwardly under the tension of the spring 16 so that the outer end of the rod which constitutes the firing pin will strike the cap fuse in the shell for the exploding of the cartridge 13 and the consequent sounding of the alarm for indicating the presence of the enemy in the immediate vicinity. In this connection it is to be observed that the guide 23 is formed within 30 and near the outer or upper end of the cas-

ing for properly directing the firing pin or rod 14 in moving towards the cartridge.

It is believed that in view of the foregoing description, a further detailed description of the operation of the invention is entirely 40 unnecessary. Likewise, it is believed that the advantages of the invention will be readily apparent.

Having thus fully described the invention, what is claimed as new and desired to be secured by Letters Patent is:

A device for the purpose indicated embodying a cylindrical casing, a spring actuated plunger carried within the casing and provided with a cap engaging element, 50 means for holding a cap in position at the top of the casing to be engaged by the cap engaging element of the plunger upon the expansion of the spring of the latter, the casing being formed at an intermediate 55 point with a transverse slot and with an ear whose upper face lies in the plane of the bottom face of the slot, the ear being spaced from the extremity of the slot, and a trip arm pivotally connected with said ear and adapted to enter the slot to obstruct the path of movement of the plunger to retain the same in retracted position, the free extremity of the trip arm being provided with an ear for the attachment of means by which 60 said arm may be swung out of obstructing position with relation to the plunger.

In testimony whereof I affix my signature.

CHARLES H. McDONALD.
